UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed August 24, 1923. Serial No. 659,116.

My invention relates to carriage feeds or escapement mechanism for typewriting machines and its object is to provide new and improved mechanism of the character stated.

5 To the above and other ends which will hereinafter appear, my invention consists in the features of construction, combinations of devices and arrangements of parts herein-after described and particularly pointed out 10 in the claims.

In the accompanying drawings which illustrate the preferred form of my invention applied to a Smith Premier No. 60 typewriting machine.

15 Figure 1 is a fragmentary side elevation partly in section showing the train of connections between the key operated universal bar and the escapement dog rocker, together with one of the type bars which actuate the 20 train.

Figure 2 is a fragmentary rear elevation showing some of the parts of Figure 1.

Figure 3 is a top plan view of the dog rocker and dogs drawn to an enlarged scale, 25 one of the escapement wheel teeth being shown in section.

Figure 4 is a top plan view like Figure 3 but showing the dog rocker in operated position.

30 Figure 5 is a view corresponding to Fig. 3 but showing the fixed or holding dog in a re-set or re-adjusted position.

Figure 6 is a horizontal sectional view taken on a plane indicated by the section line 1 in Figure 1 and looking downward 35 in the direction of the arrow at said line, said Fig. 6 however being drawn to a larger scale than Figure 1.

Figure 7 is a fragmentary vertical sectional view taken on a plane indicated by the section line 2-2 in Fig. 3 and looking in the direction of the arrow at said line, parts being broken away.

40 Figure 8 is a vertical sectional view taken on the plane indicated by the section line 3-3 in Fig. 3 and looking in the direction of the arrow at said line.

Only so much of the machine is shown herein as is necessary to a complete understanding of the invention, a somewhat fuller disclosure of the Smith Premier No. 60

machine appearing in my co-pending application, Sr. No. 653,683, filed July 20, 1923. The type bars of the machine are horizontally arranged in an arc below the platen, one 55 of the middle type bars being shown in Figure 1 and numbered 1. The type bars are mounted on a common pivot wire 2 which is supported on a vertically disposed segmental type bar support 3, said support 60 being formed with radial slots 4 in each of which one of the type bars is arranged and guided. Rigid with the segment proper is a supplemental frame 5, the segment 3 and the frame 5 being adapted to be shifted vertically on the main frame of the machine to change case. The lower case position of the segment 3 and shift frame 5 is illustrated in Figure 1, and it is to be understood that key operated mechanism is employed 70 to shift the segment 3, the frame 5, and the type bars supported thereon, downward for upper case positions. The free end portions of the type bars are supported on a rest 6 which is connected with the shiftable parts 75 and shifts down and back with them, so that the relationship of the type bars on their support is not altered as a result of shifting movements. Each type bar carries two types, a lower case type 7 and an 80 upper case type 7^a, the upper case type 7^a being brought into position for co-operation with the platen when the segment is shifted downward. Each type bar is connected at its heel by a rearwardly extending link 8

5 with the upper end of a lever 9 comprised in the train of key operated actuating devices for the type bar. Forward of its pivot 2 as it lies in the basket each type bar is provided with a contact face 1^a which is 85 adapted to co-operate with the forward edge of a curved universal bar 10 which is arranged in an arcuate groove indicated at 11 formed in the rear face of the type bar segment 3. Guiding devices for the universal bar comprise a pin 12 carried by an extension 13 from the universal bar and slidably engaging in a guide opening 14 in the segment. At its sides, the universal bar 10 is provided with rearwardly extending arms 15, each pivotally connected at 16 with the forked upper end portion of a 90 95 100

crank arm 17, said crank arms extending upward from a rock shaft 18. The arms 15 fit loosely between the forks or bifurcations at the upper ends of the arms 17, each pivotal device 16 bridging the associate fork and passing loosely through the arm 15, the oscillating frame 17, 18 providing a support and guide for the universal bar. The rock shaft 18 is pivoted at its ends on coned screw pivots 19 having supports 20 secured to the frame member 5, check nuts 21 holding the screw pivots in adjusted positions. Rising from one end portion of the rock shaft 18 is an arm 22 carrying a lateral screw 23 to which is secured the rear end of a coiled spring 24, the front end of said spring being secured to the part 5, said spring operating to pull back and restore the universal bar frame 10, 15 and the oscillator 17, 18 to normal position after actuation during which the oscillator or frame and the universal bar are relatively movable. Both the oscillator 17, 18 and the universal bar are mounted to participate in the case shifting movements of the type bars and their support so that the action of the type bars on the universal bar is the same in both lower and upper case positions. A central arm 25 rising from the rock shaft 18 terminates in forks or bifurcated portions 26 bridged by a shouldered screw 27 which is engaged by the forked forward end of a link or connector 28, said fork fitting loosely between the bifurcations 26. The connector 28 extends rearward and is forked or bifurcated at its rear end to engage with a grooved stud 29 projecting laterally from the lower end portion of an arm 30 adjustably secured to the rear face of a dog carrier or rocker 31. Said rocker in itself is of ordinary construction and comprises an upright portion 32 rising from a horizontal cylindrical portion 33, and has also a horizontally extending portion 34. The ends of the cylindrical portion or barrel 33 receives stationary coned pivot screws 35 that are threaded through lugs 36 projecting rearward from a bracket 37 depending from the top plate 38 of the machine. Projecting upward through the rock arm 34 is a stop screw 39, the point of which normally contacts with the under face of the bracket 37, the rocker being mounted in this position by a rocker spring 40. The screw or stop 39 limits the backward swing of the rocker on its pivots 35, the forward swing of the rocker being limited by a stop screw 41 carried by the arm or part 32 and adapted to contact with a stop lug 42 on the bracket or rocker support 37. The upper end portion of the arm 32 is enlarged to provide a head which is formed at one side with two recesses or notches 43 and 44 in which escapement dogs 45 and 46 are respectively loosely housed or arranged. A pivot pin 47 ar-

ranged transversely of the plane of the escapement wheel, said pin extending through the rocker arm and bridging the recesses 43 and 44, provides a common pivot for the two dogs 45 and 46. The dog 45 is a stepping dog that is constantly pressed outward above its pivot by a coiled dog spring 48, the toothed or upper end of said stepping dog normally engaging with one of the teeth 49 of an escapement wheel or rack member 50 that is connected with the traveling platen carriage (not shown). The dog 46 or holding dog is of novel construction and mounting, said dog being in the form of a block having at its upper end a tooth or projection 51 provided with a beveled working face 52 that is adapted to engage with the working face of the escapement wheel teeth 49. The holding dog 46 is loosely pivoted on the common pivot 47 but is held from turning on said pivot by two screws 53 and 54 that are threaded through the dog, one above and one below the pivot 47, the inner ends of said screws abutting against the side of the rocker arm 32. These screws serve a double purpose. In the first place, they hold the dog 46 in fixed relationship with the rocker and in the second place they allow of an adjustment of the dog to vary the position of the beveled working face 52 of the tooth 51. By unscrewing one of the screws 53 and 54 and correspondingly screwing in the other screw, the working face 52 is moved slightly towards or away from the rocker, thus slightly varying the drop. This is illustrated in Figure 5 which as compared with Figure 4 shows the tooth 51 set slightly further away from the rocker so as to give a little less drop when the escapement mechanism is actuated. The actuation of the universal bar and the escapement devices is effected from the type bar whose contact face 1^a acts, as the type bar under its key stroke nears the platen, against the universal bar 10 moving it rearward and causing it to swing the oscillator 17, 18 rearward on the pivots 19. The rearward swing of the oscillator is transmitted to the dog rocker through the link or connector 28 which thrusts rearward against the stud 29 and arm 30, swinging the dog rocker on its pivots 35 and carrying the stepping dog 45 forward from the position shown in Figs. 2 and 3 to the Fig. 4 position. Fig. 4 shows the stepping dog disengaged from the wheel tooth 49 and the beveled face 52 of the holding dog engaged therewith. When the stepping dog is released from the escapement wheel or rack member 50 the spring 48 swings said dog on its pivot 47 to the position shown in Fig. 4 and by dotted lines in Fig. 8. On the release of the actuated key, the type bar will return to normal position allowing the restoring spring 24 to restore the

universal bar and oscillator, the rocker spring 40 restoring the dog rocker to the Fig. 1 position, the stepping dog 45 re-entering the plane of the escapement 5 wheel and engaging with the next advancing tooth thereof, thus permitting a feeding movement of the carriage to the extent of a letter space. The novel holding dog construction is comparatively simple yet quite 10 effective, allowing as it does, for an extremely accurate adjustment of the beveled working face by the same means as holds the dog from pivoting.

The connection between the universal bar 15 and the dog rocker comprising the link 28, while comparatively simple, results in so connecting the non-shifting dog rocker with the shifting universal bar and oscillator as to give similar results whether the type bars 20 are actuated in lower case or upper case position. This uniformity of operation is due primarily to the arrangement of the link 28. During case shifting operations the link 28 pivots on the stud or pin 29 25 which remains stationary, the upward end of said link swinging downward by reason of its connection with the screw 27 which participate in the case shift. Normally, or in lower case, the link 28 is inclined upward 30 from rear to front at an angle to the horizontal and is so disposed that as a result of the shift it swings downward below the horizontal to substantially the same extent that it started from above the horizontal. 35 In other words, taking the full-line or lower case position of the link 28 in Figure 1 and comparing it with its dotted line or upper case position, it will be found that a horizontal line through the center of rotation, 40 that is through the axis of the pin 29, will substantially bisect the angle formed by the lower case and upper case positions of the link. The result is that the motion transmitted from the oscillator to the dog rocker 45 will be substantially the same whether the link is in lower case or upper case position.

Various changes may be made without departing from my invention.

What I claim as new and desire to secure by Letters Patent, is:—

1. In escapement mechanism for type-writing machines, the combination of a dog carrier having fixed pivots, a pair of dogs having a common pivot separate from the carrier pivots, both of said dogs being 55 adapted to turn or receive rotary movements on said common pivot, and means independent of the common pivot for fixing the relationship of one of said dogs thereto.

2. In escapement mechanism for type-writing machines, the combination of a dog carrier, a pair of dogs mounted on said carrier and having a common pivot on which both dogs may turn or rotate, and means independent of the pivot for fixing the relationship of one of said dogs thereto, said means comprising adjustable screws carried by said last mentioned dog at opposite sides of said pivot.

3. In escapement mechanism for type-writing machines the combination of an escapement wheel, a dog carrier, a stepping dog, a holding dog having a beveled working face, a common pivot for said dogs extending transversely of the escapement 75 wheel and means for adjustably securing the holding dog on said pivot so as to vary the position of its beveled working face.

4. In escapement mechanism for type-writing machines, the combination of a dog 80 carrier, a rack member, a stepping dog, a holding dog pivotally supported on said carrier, and means for both holding said dog in fixed relationship to said carrier and also for adjusting its working face to vary 85 its place of engagement with said rack member.

Signed at the borough of Manhattan, city of New York, in the county of New York, and State of New York, this 22nd day of 90 August, A. D. 1923.

EDWIN E. BARNEY.
